OTHER PUBLICATIONS

A picture of a woman wearing a cap with filaments, as shown on golden-apples.blogspot.com, dated Aug. 31, 2006 (1 page).*

Primary Examiner—Elizabeth A Albert

Assistant Examiner—Karen E Eldridge Powers

(74) *Attorney, Agent, or Firm*—Michael A. Myers; Botkin & Hall, LLP

(57) **CLAIM**

The ornamental design for a novelty cap with filaments, as shown and described.

DESCRIPTION

FIG. 1 is a front perspective view of a first embodiment of our novelty cap with filaments showing our new design;

FIG. 2 is a side view of the novelty cap with filaments of FIG. 1;

FIG. 3 is a top view of the novelty cap with filaments of FIG. 1;

FIG. 4 is a bottom view of the novelty cap with filaments of FIG. 1;

FIG. 5 is a front view of the novelty cap with filaments of FIG. 1; and,

FIG. 6 is a rear view of the novelty cap with filaments of FIG. 1.

The phantom lines shown in the Figures are for purposes of showing the environment only and form no part of the claimed design.

The stippling shown in the drawings is shading and forms no part of the claimed design.
